CLAIM

The ornamental design for a cart with transposable support bars, substantially as shown and described.

DESCRIPTION

FIG. 1 is a front, perspective view of a first embodiment of a cart with transposable support bars;

FIG. 2 is a top view thereof;

FIG. 3 is a bottom view thereof;

FIG. 4 is a front view thereof;

FIG. 5 is a rear view thereof;

FIG. 6 is a right-side view thereof;

FIG. 7 is a left-side view thereof;

FIG. 8 is a front, perspective view thereof, with the support bars in a second orientation;

FIG. 9 is a front, perspective view of a second embodiment of a cart with transposable support bars;

FIG. 10 is a top view thereof;

FIG. 11 is a bottom view thereof;

FIG. 12 is a front view thereof;

FIG. 13 is a rear view thereof;

FIG. 14 is a right-side view thereof;

FIG. 15 is a left-side view thereof; and,

FIG. 16 is a front, perspective view thereof, with the support bars in a second orientation.

The broken lines in the drawings are for the purpose of illustrating portions of the cart with transposable support bars.
